VACUUM TUBE DEVICE

Arthur L. Wilson, Los Angeles, Calif., assignor to
Westinghouse Electric & Manufacturing Com-
pany, a corporation of Pennsylvania

Application August 25, 1923, Serial No. 659,250
Renewed March 19, 1930

1 Claim. (Cl. 250—27.5)

My invention relates to thermionic devices and more especially, to the construction and operation of such devices.

In its broadest aspect, an object of my invention is to provide a device of the character described, which is particularly designed for use as a high-capacity power tube in wireless transmission systems.

More specifically, another object of my invention is to provide a power tube which is characterized by its simplicity of design, ruggedness of construction and high operating efficiency.

A further object of my invention is to provide a high-capacity power tube embodying such construction as to provide for the ready removal of the energy dissipated at the operating elements thereof.

In a practical embodiment of my invention, the foregoing desired results are obtained by providing an elongated double-walled tubular member, the inner and outer walls of which function respectively as a control electrode and as an anode element. A cathode is positioned in the annular chamber formed by said walls and is supported from opposite ends of the tubular member. The heat energy dissipated in the tube during normal operation may be carried away by causing a circulation of air, oil or other cooling medium around the inner and the outer walls of the device, all as explained more fully hereinafter.

Other objects and applications of my invention, as well as details of construction and operation, whereby my invention may be practiced, will be apparent more fully hereinafter when taken in connection with the accompanying claim, description and drawing, wherein

Fig. 1 is a view, partially diagrammatic and partially in longitudinal section, of circuits and apparatus embodying my invention, and

Fig. 2 is a section on line II—II of Fig. 1.

In the illustrated embodiment of my invention shown in the drawing, I provide a power-tube 2 and 3 designed to serve as electrodes comprising a pair of concentrically positioned metallic cylinders, the difference in diameters thereof being determined by the desired relative spacing between said metallic elements. Although I have spoken of these elements as cylindrical and the space between them as annular it is to be understood that other shapes may be used and that the inner element need not be concentric with the outer one. The cylinders 2 and 3, which may be made of any non-porous metallic substance, as for instance, copper, are insulatingly spaced and

supported and the annular space defined by the walls of the two cylinders 2 and 3 is formed into a closed chamber 4 by mounting the opposite ends thereof in rings 5 and 6, respectively, of some insulating, non-porous material, as quartz 5 or glass.

The end portions of the concentrically disposed cylinders 2 and 3, which are embedded in the rings 5 and 6, are sealed in any well-known manner to permit maintaining the annular chamber 4 in an evacuated condition, the evacuation being effected in any well-known manner. The larger cylinder 2 which preferably serves as an anode by reason of its greater heat dissipating surface, may be connected to external circuits 10 (not shown) by means of a conductor 7 extending from a point on the outer surface thereof. The remaining cylindrical member 3 may be caused to function as a control electrode by connecting the same through a conductor 8 20 which extends from the exposed surface thereof, to external circuits (not shown).

A pair of conducting annular members 9 and 11 are positioned in the evacuated annular chamber 4 immediately adjacent to the opposite 25 end portions thereof and are supported by a plurality of carrier rods 12 and 13, respectively. A plurality of filament elements 14 may be positioned in the space between said carrier rings 9 and 11 and supported thereby in such manner 30 that the several filaments 14 constitute a cylindrical surface which is positioned intermediate the containing-wall electrodes 2 and 3. The filament 14 may be connected with external terminal conductors 15 and 16 by extending one or 35 more of the carrier rods 12 and 13 through the sealing rings 5 and 6, respectively.

The energy which is dissipated in the tube device 1 during normal operation thereof is carried away by circulating air or other cooling 40 medium as oil around past the exposed portions of the tube, as previously stated. In the drawing, one method for accomplishing this is shown wherein the power tube 1 is immersed in a receptacle 17 containing oil 18, circulation 45 being provided through inlet and outlet passages 19 and 21, respectively, in the general direction indicated by the arrows.

While I have shown only a specific embodiment of my invention for the purpose of describing 50 the same and illustrating its principles of construction and operation, it is apparent that various changes and modifications may be made therein without departing from the spirit and scope of my invention. I desire, therefore, that 55

only such limitations shall be imposed thereon as are indicated by the appended claim or as are demanded in the prior art.

I claim as my invention:

- 5 A vacuum tube of annular form comprising a metallic outer wall and a metallic inner wall constituting electrodes of the tube, non-metallic end portions, each sealed to both of said walls, two pluralities of standards, one plurality
10 mounted in each of said end portions, each

standard extending into the space between said walls, two ring-shaped conductive members, one secured to each plurality of said pluralities of standards, a cathode comprising a plurality of lengths of filament between said ring-shaped members, one standard of each of said pluralities of standards being conductive and extending through the respective end portion, whereby heating current may be conveyed to said cathode.

ARTHUR L. WILSON. 10
